UNITED STATES PATENT OFFICE

CLAUDE THEODORE SIEBS, OF NUTLEY, NEW JERSEY, ASSIGNOR TO WESTERN ELECTRIC COMPANY, INCORPORATED, OF NEW YORK, N. Y., A CORPORATION OF NEW YORK

APPROACH STRUCTURE BETWEEN DIFFERENT LEVELS AND METHOD OF PRODUCING THE SAME

Application filed October 8, 1928. Serial No. 310,986.

This invention relates to approach structures between different levels and a method of producing the same, and more particularly to a ramp structure and a method of its production.

This invention has been found particularly useful when resurfacing a floor of a room, or a building, which is of the same level as the floor of an adjacent or adjoining room or building, or of one floor portion with another portion thereof, with a cementitious composition, such as magnesite. As has been practiced, instead of removing the floor material of the area which is to be resurfaced, it is used as a foundation for the cementitious composition. Thus a difference in floor levels results which necessitates an inclined approach or ramp structure between these levels.

The objects of this invention are a simple approach structure which may be readily and quickly installed and one possessing wear resisting and anti-slipping properties, and an economical method of producing it.

In accordance with the aforementioned objects the present invention contemplates a ramp structure including a framework comprising a flat body portion with upturned tapering flanges at opposite edges thereof and provided with a plurality of perforations in the body portion. When installing the ramp structure between different levels the framework is angularly positioned with its front edge loosely secured to the floor at the edge of the portion of the floor being resurfaced with its flanges turned upwardly. The cementitious floor composition is then positioned underneath the ramp structure, following which it is pressed downwardly against the composition. Thus the composition is extruded into the perforations in the body portion to form isolated areas of the magnesite surrounded by a flush metal surface, the upturned flanges serving as retaining walls for the composition at either end of the ramp structure. A small percentage of carborundum may be introduced into the portion of the magnesite upon which the ramp structure is laid to provide increased wear resistance and anti-slipping properties.

Other objects and advantages of this in-

vention will more clearly appear from the following detailed description taken in connection with the accompanying drawing, wherein

Fig. 1 is a plan view of a resurfaced floor 55 wherein a difference in floor levels results with an approach structure embodying the features of this invention between the levels;

Figs. 2 and 3 are enlarged fragmentary detail sections on the lines 2-2 and 3-3, 60 respectively, thereof;

Fig. 4 is a perspective view of a member forming the framework of the approach structure, and

Fig. 5 is a view illustrating a step in the 65 method of producing the approach structure of this invention.

Referring now to the drawing in detail wherein like reference numerals designate similar parts throughout the several views 70 a sub-floor structure 10 supports a floor 11, one portion of which has been resurfaced with a cementitious composition 12, which may be a composition of the oxide chloride type, such as magnesite, which has been found 75 suitable for this purpose. This magnesite composition is preferably applied in a plastic state with a suitable coloring matter added thereto to give the desired color effect and then troweled to provide a suitable surface 80 as desired. Before applying the magnesite 12 to the floor to be resurfaced a layer of slater's felt 13 and above that an expanded metal plate 14 is laid on the floor and fixed thereto, the expanded plate serving as an 85 anchorage for the magnesite composition upon hardening.

The floor portion to be resurfaced, in some instances, may be divided from the rest of the floor by a partition or wall or there may 90 be no structural division, the latter condition being illustrated in the drawing. A retaining wall 17 is used to prevent the plastic magnesite 12 from flowing onto the portion of the floor not to be resurfaced and forms a 95 permanent end for the resurfaced floor portion. A metal member 18 forming the framework of the approach structure comprises a flat body portion 19 with upturned tapering flanges 20 at opposite edges thereof and pro- 100

vided with a plurality of perforations 21 in the body porton. The upturned tapering flanges 20 serve as retaining walls for the magnesite at either end of the approach or ramp structure and at their greatest height are substantially equal to the depth of the magnesite 12 laid on the resurfaced floor portion. When ready to install the ramp structure, the framework 18 is angularly positioned with its front edge loosely secured to the floor 11, at the edge of the portion thereof being resurfaced with its flanges turned upwardly, by means of nails or screws 22 inserted through a plurality of the perforations 21 at the front edge of the body portion 19. This step is clearly illustrated in Fig. 5. Thereafter a quantity of the plastic magnesite 12 is forced underneath the framework 18 up to the front edge thereof. The framework 18 is then lowered, pressed and tamped to the required position and fastened permanently with a plurality of flat head wood screws 23 inserted through suitable apertures provided in the framework, through the expanded metal plate 14 and into the wood floor 11 as shown in Figs. 2 and 3. The felt 13 and expanded metal plate 14 it will be observed extend under the framework 18 for only such a distance (Figs. 2 and 3) which will permit the lower surface of the body portion 19 adjacent the framework edge of the framework to lie firmly against the floor 11.

In pressing and tamping the framework into position the plastic magnesite 12 underneath is extruded into the perforations 21 in the body portion 18, thus forming isolated areas of the magnesite surrounded by a flush metal surface. A small percentage of carborundum is preferably introduced into the portion of the magnesite upon which the framework 18 is laid to provide increased wear resistance and anti-slipping properties.

In practice, approach or ramp structures of the hereinbefore described type have proven very satisfactory from a life standpoint, as well as the standpoint of economy in producing them. Furthermore, due to the extrusion of the plastic magnesite with the carborundum introduced therein through the apertures of the metal approach framework a very efficient tractive surface is provided, and one tending to eliminate accidents due to slipping on the inclined portion of the structure.

Although the invention has been disclosed and described in connection with a particular type of floor construction, it is to be understood that the invention is capable of other applications and should be limited only by the scope of the appended claims.

What is claimed is:

1. An inclined approach for joining different levels, comprising a member having a body portion joining the different levels with

upturned tapering flanges at opposite edges thereof, the body portion provided with perforations, and a material filling the perforations differing from that of the material composing the member to provide a tractive surface joining the levels.

2. An inclined approach for joining different levels, comprising a cementitious composition containing an abrasive between the different levels, and a member having a perforated body portion mounted in position upon the cementitious composition before cementation thereof occurs and joining the levels, the composition being extruded into the perforations of the member to provide an exposed tractive surface joining the levels.

3. The method of producing an inclined approach at the junction of different levels, which consists in depositing cementitious composition at the junction of the levels, and then forming the composition between the levels by pressing downwardly thereon a perforated member whereby portions of the cementitious composition are extruded into the perforations, and exposing portions of the cementitious composition to provide a tractive surface joining the levels, the member first being engaged with the lower of the levels and swung downwardly into engagement with the higher level.

4. A floor member for an inclined approach, comprising a flat metallic plate having spaced perforations designed to permit the extrusion of cementitious material therethrough, and a pair of tapered integral flanges at opposite edges of the plate adapted to serve as retaining walls for cementitious material.

5. A floor member for an inclined approach comprising a flat metallic plate having spaced perforations designed to permit the extrusion of cementitious material therethrough, and an integral flange at one side of the plate adapted to serve as a retaining wall for the cementitious material.

In witness whereof, I hereunto subscribe my name this 24th day of September A. D., 1928.

CLAUDE THEODORE SIEBS.
